UNITED STATES PATENT OFFICE

2,163,298

INTERCHANGEABLE ILLUMINATED SIGN

Charles J. Wamser, Milwaukee, Wis.

Application May 16, 1938, Serial No. 208,193

3 Claims. (Cl. 40—140)

This invention pertains to interchangeable signs, and more particularly to electrically illuminated signs provided with translucent or opalescent glass panels, and opaque or translucent silhouette letters detachably mounted thereon.

The invention has primarily for its object to simplify and reduce the cost of manufacture of signs of the foregoing type, such as disclosed in United States Letters Patents Nos. 2,038,078, 10 2,048,040, and 2,113,285, by the provision of novel means for detachably mounting the silhouette letters upon the front face of the illuminated translucent panel.

Incidental to the foregoing, a more specific object resides in connecting and supporting a pair of spaced, parallel, horizontal channels directly upon the front face of a translucent panel, thus eliminating an expensive supporting frame for the letters, and reducing obstruction of illumination to a minimum.

Another object of the present invention resides in the fact that the silhouette letters are positioned closely adjacent the translucent panel, thus providing a clean-cut outline for the letters, which materially enhances the appearance of the sign.

With the above and other objects in view, which will appear as the description proceeds, the invention resides in the novel construction, combination, and arrangement of parts, substantially as hereinafter described, and more particularly defined by the appended claims, it being understood that such changes in the precise embodiment of the herein disclosed invention may be made as come within the scope of the claims.

In the accompanying drawing is illustrated one complete example of the physical embodiment of the present invention constructed according to the best mode so far devised for the practical application of the principles thereof.

In the drawing:

Figure 1 is a front elevation of a sign constructed in accordance with one form of the present invention, parts being broken away and in section to more clearly illustrate structural details.

Figure 2 is a transverse section taken on the line 2—2 of Figure 1; and

Figure 3 is an enlarged fragmentary detail section taken on the line 3—3 of Figure 1.

Referring now particularly to the accompanying drawing, while a sign of the present type has numerous applications it is particularly designed for use in connection with theatre marquees, in

which it is desired to frequently change the display letters.

The numeral 1 designates generally a frame in the form of a housing, comprising top and bottom walls 2 and 3, respectively, to which is attached a rear wall 4. Secured to the front of the housing, which is normally open, is a translucent or opalescent panel 5, formed of glass or other suitable material. To provide for quick removal of the panel 5 for cleaning, or to permit access to the housing, the panel 5 is mounted between longitudinal lips 6 extending from the top and bottom walls 2 and 3 of the housing. As best shown in Figure 2, the height of the panel 5 is somewhat less than the distance between the top and bottom walls of the housing, thus allowing the panel to be shifted upwardly to clear the lower lips, after which it can be swung outwardly at its lower edge and withdrawn from the top lips of the housing.

The housing is illuminated by an incandescent bulb 7 mounted upon a ledge 8 supported upon the bottom wall 3. Obviously, other forms of illumination, such as gas discharge tubes and the like, may be employed without departing from the invention.

The structure heretofore described is more or less conventional, the salient principles of the invention residing in the novel means for mounting the detachable silhouette letters upon the front of the translucent panel 5. Heretofore, structures of the present type, such as disclosed in the patents referred to, have resorted to auxiliary frames carried by the housing independently of the translucent panel, or surrounding the edges of the panel and suitably secured thereto. Such frames are not only expensive, but also create obstruction to the illumination, which is particularly objectionable in signs utilizing a plurality of translucent panels, such as is customary in marquees. In other words, such frames cause a marked division between the panels, which detracts from the general appearance of the sign.

To overcome the foregoing objections, the present invention entirely eliminates an independent fabricated letter frame by the provision of spaced upper and lower parallel channels 9 and 10, respectively, to which threaded studs 11 are secured in any suitable manner and projected through openings 12 provided in the panel 5. Nuts 13, threaded upon the rear ends of the studs 11, serve to firmly lock the channels to the glass.

The silhouette letters or characters 14 may be formed in any desired manner from various ma-

terials. However, for the purpose of economy it is contemplated to stamp or cut the same from weather-resistance fibrous or composition material. The upper and lower edges of the characters 14 are provided with nibs or projections 15, which extend into the channels 9 and 10, and as will be noted in Figures 1 and 2 of the drawing, a clearance is normally provided between the projections 15 and the top of the upper channel 10, which allows insertion or removal of the letters from the channels by shifting the same upwardly to permit clearance of the lower channel.

Inasmuch as the weight of the letters is supported largely by the lower channel 10, the same is preferably formed in a Y configuration in cross section, which provides a relatively shallow channel to facilitate removal of the letters, and at the same time affords sufficient contact between the channel and panel to prevent sagging of the channel. While the channel 10 can be formed in any desired manner, it is preferred to stamp the same from sheet material, bent back upon itself, and having one of its edges beaded over the adjacent edge to securely lock the two together, thus providing a relatively inexpensive and at the same time rigid construction.

While the dimensions of the channels with relation to the characters and other portions of the sign illustrated in the drawing are considerably exaggerated for the purpose of more clearly showing structural details, it will be appreciated from the explanation given in connection with the accompanying drawing that the present invention provides a very simple and relatively inexpensive structure for detachably supporting silhouette letters upon the front of an illuminated translucent panel, and in close proximity to the panel, providing clean-cut outlines for the characters highly desirable in a sign of the present type.

Further advantages of the invention result from the fact that no obstruction is required between adjacent panels, such as occurs in conventional

signs of the present type, and being directly connected to the translucent panel at suitably spaced points, the channels 9 and 10 further serve as a reinforcing means for the panel to prevent breakage from wind or other causes, and also, in the event of breakage, acting to hold the parts of the panel, thus preventing them from falling to the sidewalk or highway and injuring pedestrians.

I claim:

1. An illuminated sign comprising a housing 10 having an open side, electric illuminating means contained within said housing, a translucent panel detachably carried by said housing, a pair of spaced parallel horizontal channels, means carried by the channels and projecting through said panel for detachably securing the channels thereto, and silhouette letters having upper and lower projections detachably mounted in said channels.

2. An illuminated sign comprising a housing having an open side, electric illuminating means 20 contained within said housing, a translucent panel detachably carried by said housing, a pair of spaced parallel horizontal channels, threaded studs carried by the channels and projecting through said panel for detachably securing the channels thereto, and silhouette letters having upper and lower projections detachably mounted in said channels.

3. An illuminated sign comprising a housing having an open side, electric illuminating means 30 contained within said housing, a translucent panel detachably carried by said housing, a pair of spaced parallel horizontal channels, the lower channel being of Y configuration in cross section, and having a flat side in contact with said panel above and below the crotch of the channel, means 35 carried by the channels and projecting through said panel for detachably securing the channels thereto, and silhouette letters having upper and lower projections detachably mounted in said 40 channels.

CHARLES J. WAMSER.
